IGNITION APPARATUS

Charles H. Davis, Jr., deceased, late of Anderson, Ind., by John T. Fitzsimmons, administrator, Anderson, Ind., assignor to General Motors Corporation, Detroit, Mich., a corporation of Delaware

Original application February 11, 1932, Serial No. 592,289, now Patent No. 2,016,669, dated October 8, 1935. Divided and this application July 25, 1934, Serial No. 736,845

8 Claims. (Cl. 287—52)

This invention relates to ignition timing distributor units for internal combustion engines and particularly for engines having a relatively large number of cylinders or spark gaps and requiring the use of a relatively massive ignition timer cam and distributor rotor and is a division of the copending application S. N. 592,289 filed February 11, 1932, now matured into Patent No. 2,016,669, of October 8, 1935.

Some trouble has been experienced with ignition timer distributor units for multi-cylinder engines because upon sudden acceleration of the engine a relatively heavy strain is placed upon the driving connections between the main drive shaft of the timer distributor unit and the cam and distributor rotor. This difficulty is encountered particularly because of the unusual mass of the cam and rotor to be accelerated whenever the engine is suddenly accelerated. It is an object of the present invention to overcome these difficulties by certain improvements in the construction of the driving connections leading to the cam and distributor rotor.

Further objects and advantages of the present invention will be apparent from the following description, reference being had to the accompanying drawing wherein a preferred embodiment of one form of the present invention is clearly shown.

In the drawing:

Fig. 1 is a longitudinal sectional view of an ignition timer distributor unit embodying the present invention.

Fig. 2 is a sectional view on the line 2—2 of Fig. 1.

Fig. 3 is a perspective view of a portion of the driving connection leading to the timer cam and distributor rotor.

Figs. 4, 5, and 6 are plan views of modified forms of the driving member shown in Fig. 3.

Referring to Fig. 1, the numbers 20 and 21 designate ignition timer housing members secured together by screws such as shown at 22 thereby enclosing a chamber 23 which receives a centrifugal device for controlling the timing of the ignition. The member 20 provides a tubular shank 24 received by a well in an engine frame which supports the timer. The shank 24 provides a bearing 25 for a shaft 26 carrying a gear 27 which meshes with a gear driven by the engine. The shaft 26 carries adjacent its upper end a collar 28 which is supported upon a thrust washer 29 bearing against an upper end of a tubular boss 30 which is in effect an extension of the shank 24. The shaft 26 is attached at its upper

end to a weight plate 31 which bears against the collar 28 and which is attached by riveting over the annular end portion 32 of the shaft 26, said end portion surrounding an internal bore 33 of the shaft 26. The plate 31 carries studs 35 which pivotally support laminated weights 36 spot welded together and slideable across ribs 38 formed in the plate 31. The weights 36 have lever arms 39 cooperating with lever arms 40 of a bar 41.

Pins 50 secure together the bar 41, a spacer 10 plate 45 and a weight retainer plate 46 coextensive with the plate 45 and having wings 47 which are offset from the portion 46 and which extend over the weights 36 to retain them loosely upon the ribs 38. The parts 41, 45, and 46 have 15 central holes which are aligned when these parts are assembled by the pins 50. The wall of the central hole through this assembly of parts is serrated and then the assembly is hardened and is pressed on an unhardened portion 42 of a cam 20 carrying shaft 43 whose lower end portion 44 has a bearing in the internal bore 33 of the shaft 26.

One of the pins 50 is longer than the other and extends into a hole 51 in the weight plate 31, the hole 51 being of a size such as to provide a 25 means for stopping movement of the pin 50 within a prescribed range of movement. The weights 36 are urged toward the shaft by spring 52 connecting the posts 35 with the posts 50.

The posts 50 are not only connected to the 30 shaft 43 through parts 41, 45, and 46 having a drive fit therewith, but are directly connected with the shaft 43 by parallel cross-pins 53 driven through holes in the shaft 43. Each end of each pin 53 fits snugly into a groove 54 in each 35 pin 50. In this manner the part 41 which is the driving member for the shaft 43 is securely anchored to the shaft 43 in such a manner that angular displacement cannot occur without disrupting the driving fit between the parts 41, 45, 40 and 46 and the shaft part 42 and without also bending the pins 53. This construction is of course useful for ignition apparatus required to rotate in either direction.

The modified form of the part shown in Fig. 45 3 is shown in Fig. 4 in which one pin 53a is employed. This pin extends diametrically across the shaft 43 and has its ends bent so as to be received by the grooves 54 in each of the pins 50. Fig. 5 is similar to Fig. 4 with the exception 50 that two pins 53b are employed, these pins 53b have tapered inner ends driven into tapered holes in the shaft 43.

The form shown in Fig. 6 is adapted for use in a distributor which is required to rotate in one 65

direction only. One cross pin 53c is employed and the ends thereof are received snugly by the groove 54 of pins 50.

The shaft 43 is journaled in a ball bearing 60 received in a cup-shaped part 61 provided in the base of the housing 21. The inner race of the bearing 60 is retained upon a shoulder 62 of shaft 43 by a resilient C-washer 63 which is snapped into a groove 64 provided in the shaft 10 43. A spacer 65 is located between the washer 63 and the inner race of the bearing 60.

The washer 63 provides a seat for a cam 70 having a center bore which fits over the upper end of the shaft 43. The upper end of the shaft 15 43 is tubular in formation and is slit in order to provide four resilient wedging members 71 which are adapted to be wedged apart by an expanding member 72 against the inner wall of the bore of the cam 70 in order to tightly secure the 20 cam 70 on the shaft 43 in the desired position of adjustment. The expanding or wedge member 72 is formed to provide a frustro-conical wedging portion 73 and has a central bore 76 to receive a wedge screw 77 whose threaded lower end 25 screws into a hole tapped centrally in the shaft 43. The wedge 72 is permanently secured to the screw 77 by deforming the lower end of its conical portion 73, as indicated at 78 in Fig. 1, into groove 79 provided by the screw 77. The 30 cam 70 is provided with diametrically opposite notches 80 for receiving a lug 74 of the wedge 72 as shown in Fig. 1. These notches 80 are formed in a tubular extension 81 of the cam 70 which extension is received by suitably 35 formed apertures in a distributor rotor block 90 in order that the cam 70 may drive the block 90.

The tightening of the screw 77 causes the wedge 72 to move longitudinally into the shaft 43 thereby urging the prongs 71 tightly against the 40 cam 70. Since the wedge 72 is provided with lugs 74 directly drivingly connected with the cam 70 it is apparent that the cam is bound first to the shaft 43 due to friction which exists between the outer surfaces of the prongs 71 and the inner 45 wall of the cam 70 and to friction which exists between the outer conical surfaces 73 of the wedge 72 and the inner conical surfaces of the prongs 71. In this way a double binding effect is obtained by utilizing both the external and internal surfaces of the prongs 71.

The cam 70 cooperates with a circuit interrupter 85 mounted on a plate 86 supported by the housing member 21 and supporting an ignition condenser 87.

55 The rotor 90 carries a conducting rotor 91 which carries current from a center button 92 to alternate distributor posts 93. The rotor block 90 carries a conducting rotor 94 for conducting current to alternate distributor posts 93. The 60 conductor 94 is electrically connected with a brush 95 bearing against a conducting ring 96. The button 92 and ring 96 are connected, respectively, with posts 97 and 98 having threaded sockets for receiving threaded connector plugs, not 65 shown.

While the form of embodiment of the present invention as herein disclosed, constitutes a preferred form, it is to be understood that other forms might be adopted, all coming within the 70 scope of the claims which follow.

What is claimed is as follows:

1. In an ignition timer-distributor apparatus having a timer cam for operating a circuit interrupter and for driving a distributor rotor, the

combination comprising a shaft for driving the cam, a bar for driving the shaft, means for fixing the bar to the shaft, a stud connected with the bar, and a rod bearing against the stud and attached to the shaft. 5

2. In an ignition timer-distributor apparatus having a timer cam for operating a circuit interrupter and for driving a distributor rotor, the combination comprising a shaft for driving the cam, a shaft-driving bar having a driving press 10 fit with the shaft, a stud connected with the bar at a substantial distance from the shaft and extending parallel thereto, and a rod projecting transversely from the shaft and engaging the stud. 15

3. In an ignition timer-distributor apparatus having a timer cam for operating a circuit interrupter and for driving a distributor rotor, the combination comprising a shaft for driving the cam, a bar secured to and driven by the shaft, 20 studs carried by the bar, and a cross pin carried by the shaft whose ends engage said studs.

4. In an ignition timer-distributor apparatus having a timer cam for operating a circuit interrupter and for driving a distributor rotor, the 25 combination comprising a shaft for driving the cam, a bar driving the shaft and having a press fit with the same, grooved studs carried by the bar, and cross pins carried by the shaft for engagement with the grooves of said studs. 30

5. In an ignition timer-distributor apparatus having a timer cam operating a circuit interrupter and for driving a distributor rotor, the combination comprising a shaft for driving the cam, a shaft driving bar having a driving press 35 fit with the shaft, means carried by the bar and located at a substantial distance from the shaft, said means extending beyond the plane of the bar, and means projecting from the shaft and engaging the means carried by the bar. 40

6. In an ignition timer-distributor apparatus having a timer cam for operating a circuit interrupter and for driving a distributor rotor, the combination comprising, a shaft for driving the cam, a weight hold-down plate fixed to the shaft, 45 a bar fixed to the shaft and carrying studs near its extremities, and cross pins carried by the shaft and engaging the studs.

7. In an ignition timer-distributor apparatus having a timer cam for operating a circuit interrupter and for driving a distributor rotor, the combination comprising, a shaft for driving the cam, a shaft-driving assembly fixed to the shaft, 50 said assembly comprising, a spacing member, a weight hold-down member, a bar, and a stud carried by the bar and passing through the hold-down member and the spacing member to hold said members in a fixed relation with respect to the bar and to each other, and means extending from the shaft and engaging the studs. 55

8. In an ignition timer-distributor apparatus having a timer cam for operating a circuit interrupter and for driving a distributor rotor, the combination comprising, a shaft for driving the cam, a shaft-driving assembly fixed to the shaft, 65 said assembly including a retaining plate, a bar, and studs fixed to the bar and extending through the plate to hold the retaining plate in a fixed relation with respect to the bar, and means extending through the shaft and bearing against 70 the studs.

JOHN T. FITZSIMMONS,
Administrator of the Estate of Charles H. Davis,
Jr., Deceased.
